COMBINED CLOCK AND PERPETUAL CALENDAR

Garry M. Carthew, North Hollywood, Calif., assignor to
Peter Pepper Products, Inc., Lomita, Calif., a corpora-
tion of California

Filed Mar. 23, 1959, Ser. No. 55,135

Term of patent 14 years

(Cl. D42—7)

Figure 1 is a perspective view of a combined clock and perpetual calendar showing my new design; and Figure 2 is an end view of said clock.

The essential features of the design reside in the portions shown in full lines, while the movable magnetic rings shown in broken lines are for illustrative purposes only.

I claim:

The ornamental design for a combined clock and perpetual calendar, substantially as shown and described.
